UNITED STATES PATENT OFFICE.

ALBERT P. STOCKER, OF STRUTHERS, OHIO.

BRACE FOR SHEET-METAL PILES.

No. 886,089.

Specification of Letters Patent. Patented April 28, 1908.

Application filed January 31, 1908. Serial No. 413,592.

To all whom it may concern:

Be it known that I, ALBERT P. STOCKER, a citizen of the United States of America, residing at Struthers, in the county of Mahoning and State of Ohio, have invented certain new and useful Improvements in a Brace for Sheet-Metal Piles, of which the following is a specification, reference being had therein to the accompanying drawing.

10 This invention relates to a brace for sheet metal piles, and the primary object of my invention is, to provide a brace that can be used in connection with freight cars for maintaining metallic sheets, rods, bars and structural iron in a pile in the car.

Another object of this invention is to provide a simple and inexpensive brace that can be easily placed in position to retain pieces of material in an orderly group or pile.

20 My invention will be presently described and then specifically pointed out in the appended claims.

Referring to the drawings: Figure 1 is a side elevation of a brace constructed in accordance with my invention, Fig. 2 is a plan of the same, and Fig. 3 is an end view.

25 In the accompanying drawings, 1 designates the floor of a car and 2 the side wall thereof. Upon the floor 1 I have represented a pile of metallic sheeting 3, this sheeting being placed adjacent to the wall 2.

30 My brace comprises a plate or bar 4 having a bent end 5, by which said bar or plate is secured to the wall 2 of the car, by nails, screws or similar fastening means. The opposite end of the bar or plate 4 is bent to provide a hook 6. Adapted to engage the hook 6 of the bar or plate 4 is a metallic strip 7 having depending twisted ends 8, which are pierced 35 whereby the strip can be secured to the floor 1 by nails 9 or similar fastening means. The twisted ends 8 of the strip are formed at an

angle to the body thereof or that portion engaged by the bar or plate 4, and the ends are twisted whereby the flat or broad surface of 45 the strip 7 will lie in engagement with the edges of the metallic sheets 3, while the flat side of the plate or bar 4 engages the uppermost metallic sheet. It will thus be observed that the metallic sheeting will be 50 maintained in a pile irrespective of the vibrations to which the car may be subjected.

I do not care to confine myself to the size of the brace, or to the material in connection with which the same is used. 55

Having now described my invention what I claim as new, is:—

1. The combination with a car and a pile of material located in said car, of a brace for maintaining said material in a pile, said 60 brace comprising a bar or plate mounted upon the top of the pile and having one end secured to said car, and a strip engaging the opposite end of said plate or bar and having its ends fixed to the bottom of said car, substantially as described.

2. The combination with a car, and a pile of material located therein, of a bar or plate arranged upon the top of said pile and having one end fixed to said car, a strip engaging the 70 opposite end of said bar or plate and having its ends secured to the bottom of said car.

3. A brace of the type described comprising a bar or plate having a hook shaped end, a strip engaging the hook shaped end of said 75 bar or plate and having its ends disposed at an angle thereto.

In testimony whereof I affix my signature in the presence of two witnesses.

ALBERT P. STOCKER.

Witnesses:

HORACE L. WILSON,
J. B. BOHNER.
